UNITED STATES PATENT OFFICE.

GEORGE A. SEIB, OF ILION, NEW YORK, ASSIGNOR TO REMINGTON TYPEWRITER COMPANY, OF ILION, NEW YORK, A CORPORATION OF NEW YORK.

TYPEWRITING MACHINE.

Application filed March 23, 1922. Serial No. 546,040.

To all whom it may concern:

Be it known that I, GEORGE A. SEIB, a citizen of the United States, and resident of Ilion, in the county of Herkimer and State 5 of New York, have invented certain new and useful Improvements in Typewriting Machines, of which the following is a specification.

My invention relates to typewriting and 10 like machines and more particularly to tabulator mechanism therefor.

The main object of my present invention is to provide a detachable stop which is simple to manufacture and efficient in use, and 15 which may be adjusted to any column determining position on a stop bar and convert an existing form of column selecting tabulator into a denominational selector by its co-operation with the stop of my invention.

20 To the above and other ends which will hereinafter appear, my invention consists in the features of construction, arrangements of parts, and combinations of devices, set forth in the following description and particularly 25 pointed out in the appended claims.

In the drawings, wherein like reference characters designate corresponding parts in the different views,

Figure 1 is a fragmentary detail fore-and-aft vertical sectional view showing a portion of a No. 10 Remington typewriting machine, embodying my invention.

Figure 2 is a fragmentary plan view of a portion of the same.

35 Figure 3 is a detail fragmentary rear view of the column stop bar with the multiple stop of my invention mounted thereon.

Figure 4 is an enlarged detail transverse sectional view of the same, taken on the 40 line 4—4 of Fig. 3 and looking in the direction of the arrows at said line.

Figure 5 is a detail top plan view showing the upper portion of the tabulator frame and parts carried thereby.

45 Figure 6 is an enlarged detail perspective view of the multiple stop of my invention.

The No. 10 Remington machine includes a column selector, with features somewhat like those shown in my Patents, Nos. 50 1,132,286 and 1,273,545 dated respectively Mch. 16, 1915 and July 23, 1918. I have shown my invention embodied in such a machine, and by the simple expedient of using

the multiple stop of my present invention, 55 may convert the column selector of that machine into a denominational selector, as will hereinafter more fully appear. In the accompanying drawings I have shown only so much of the No. 10 Remington machine as is necessary to arrive at an understanding of 60 my invention in its embodiment therein.

The frame of the machine comprises a base 1, corner posts 2 and a top plate 3. The carriage 4, which supports a platen 5, is mounted to travel on anti-friction rollers 6 65 over the top plate in the usual manner under control of escapement mechanism, not shown.

A tabulator frame 7 is detachably secured to the frame of the machine by screws 8 and 9, as in my said Patent No. 1,273,545. 70 Upstanding tabulator-stop actuating levers 10 are fulcrumed on a pivot rod 11 supported at its ends by lugs or arms 12 which project forward from the tabulator frame 7. The upper forwardly extending end 13 of 75 each lever 10 coacts with a plate-like stop 14, pivoted at one end on a vertically disposed pivot 14^a. The stops 14 thus have a superposed arrangement moving in parallel horizontal planes that extend transversely of 80 the machine. These stops are provided with vertically aligned contacts 15; each stop being under control only of its associated actuating lever 10 and moving in a horizontal plane or path which differs from that of each 85 of the other stops. In the present instance five stops 14 and five actuating levers therefor are shown, though the number employed is immaterial. Each actuating lever 10 co-acts with a spring 16 which bears at one end 90 against a shoulder 17 on the tabulator frame, and at its other end against a shoulder 18 on the coacting lever, to return the lever to normal position after pressure on the associated tabulator key is released. Each stop 95 14 coacts with an independent spring 19 (see Fig. 5) by which it is returned from the projected position back to its normal position.

Each lever 10 is pivoted at 20 to a forwardly extending link 21 pivoted at its 100 forward end, as at 22, to an angular lever 23. The levers 23 are maintained spaced apart and are pivoted on a fixed pivot rod 24 secured at its ends to the frame of the machine. A forwardly projecting finger 25 105 on each lever 23 extends through an open-

ing in the stem 26 of a tabulator key 27. These keys may bear suitable indices 28, or they may be plain and suitable indices provided on a fixed flange 29 on the front plate 5 30 of the machine, as is now done in the No. 10 Remington machine. On the other hand, I prefer to provide numerical indices "1", "2", "3", "4" and "5" (indicated at 28) on the keys, reading progressively from left to 10 right, and to provide on the face of the flange 29 denominational indices 31 opposite the respective keys 27. In the present instance I have shown a series of indices "", "U", "T", "H" and "Th", reading in the 15 order named from right to left, though a different arrangement of denominational indices may be provided. The use of these two sets of indices 28 and 31 will herein-after appear.

20 It will be understood that the depression of a tabulator key is effective to project the companion stop 14 into the path of a stop on the carriage and simultaneously release the carriage by carriage releasing means, not shown.

25 In the No. 10 Remington machine the carriage is provided with arms 32 to which is fixed a toothed column stop bar 33 that carries a series (or a multiple of such series) of five individually adjustable column stops, 30 the contact on each stop of the series traveling in a different path, and in a path which is coincident with the plane of one of the stops 14. It follows therefore that the depression of a key 27, which in said machine 35 is a column selecting key, determines the columnar position of arrest of the carriage. By my present invention I contemplate employing, either in addition to or independently of the ordinary column stops, the 40 multiple stop of my invention and which is shown in detail and detached in Fig. 6. This stop is designated as a whole by the reference numeral 34, and comprises a block of metal which constitutes the body portion 45 of the stop, and is bifurcated to straddle the stop bar 33 and to be detachably fixed to and adjusted to different points along the bar. This block has bifurcated sheet metal plates 35 riveted at 36 to opposite 50 sides thereof. The parallel edge portions 37 of each plate are received in spaces between teeth 38 on opposite sides of the column stop bar 33 to hold the stop in its adjusted position on the bar. A finger piece 39 may be provided 55 on the block to facilitate its attachment to and detachment from the bar, and a spring pressed ball detent 40 may be employed to hold the stop block against accidental detachment from the bar. One of the rectangular sides of the block has a series of holes 41 drilled therein (see Fig. 7), the 60 number of holes depending on the number of stops 14 employed in the machine, which is five in the present instance. These holes are 65 arranged in an inclined line or diagonally across the face of the block. Each hole 41 receives the stem 42 of a stop pin having an enlarged head 43 that projects from the face of the block towards the rear and in the general direction of the stops 14 when 70 the block is seated on the stop bar. The point of juncture where the enlarged head of each pin joins its stem, forms a shoulder 44 that is adapted to bear against the drilled face or body portion of the block and limit 75 the extent to which each pin may be driven into its hole, and therefore insure that all of the pins will project from the face of the block a uniform distance. The holes 41 and the stems 42 of the pins are so shaped 80 and proportioned that the stems when driven into their holes will be firmly held by a "drive fit" against removal, and the pins are thus securely fixed to the block.

85 From an inspection of Figs. 3 and 4, it will be seen that the enlarged heads of the pins have an overlapping arrangement whether viewed in the direction of the length of the stop bar or at right angles thereto, and form firm substantial contacts to receive 90 the impact at each arrest of the carriage. It will be understood, moreover, that notwithstanding this overlapping arrangement of the heads of the pins the effective contact faces 45 thereof are in vertical parallel 95 planes a letter space distance apart, and are cut by parallel horizontal planes each coincident with the plane of movement of one, and only one, of the selecting stops 14. It follows therefore that the vertically aligned 100 contacts 15 on the column selecting stops 14 will coact with the pins on the stop-block 34 to denominational select the position of arrest of the carriage.

105 It is in order to indicate the key to be actuated in both column and denominational selecting that the two sets of indices 28 and 31 are provided. When column selecting, with the use of the column stops ordinarily employed, the indices 28 will be used to 110 select the first, second, third, fourth and fifth columns, depending on the particular key 27 which is actuated, and which keys are indicated by the corresponding numerals "1", "2", "3", "4" and "5". To denominational select, the indices 31 are used. For example, to write ".99" the operator should depress the decimal key indicated by the decimal mark (.). After the tabulator key is released the operator may then print the 115 decimal mark followed by the figures "99". Should the operator desire to write "9999.99" the key 27 forward of the index "Th" should be depressed and after the carriage is arrested the figures and the decimal mark may 120 be written in the order appearing above.

125 From the foregoing description it will be understood that by the very simple expedient of applying the multiple stop 34 of my invention to the ordinary form of column 130

selector used for example in the No. 10 Remington machine, it may be readily employed as a denominational selector.

What I claim as new and desire to secure 5 by Letters Patent, is:—

1. In a typewriting or like machine, the combination of a carriage, a plurality of key-controlled individually-movable column-selecting stops movable in different parallel planes that extend transversely of the machine, a toothed stop bar carried by the carriage, a multiple stop block that straddles said bar and is adjustable to different points along the bar and engages between the teeth 10 thereof, said stop block having a series of holes formed therein in an inclined line, the number of holes corresponding to the number of said key controlled stops, and a series of pins driven into said holes and firmly 15 secured to said stop block.
2. A detachable adjustable tabulator stop for typewriting and like machines comprising a bifurcated stop block, having a series of holes drilled through one rectangular side 20 thereof and in a diagonal line across the same, a series of shouldered pins driven into said holes a uniform distance with their shoulders bearing against the body portion of the block and firmly secured against detachment 25 therefrom by a drive-fit, the effective faces of said pins having different parallel paths when the stop is in use and ar- 30

ranged coincident with parallel planes arranged a letter space interval apart and extending at right angles to said paths of movement, the head of each pin which projects from the body of the stop overlapping an adjacent pin as the stop is viewed in two directions at right angles to each other.

3. In a typewriting machine and a column selecting mechanism, means for using said column selecting mechanism as a denominational selector comprising an adjustably and detachably mounted stop block bifurcated to straddle a stop rod and formed with a series of holes arranged in an inclined line, and a series of shouldered stop pins driven into said holes with their shoulders bearing against the body portion of the block and firmly secured against detachment therefrom by a drive-fit, the effective faces of said pins being cut by different parallel planes extending longitudinally of the stop rod and coincident with planes that extend transversely of said bar at letter space intervals apart.

Signed at Ilion, in the county of Herkimer and State of New York, this 21st day of March, A. D. 1922.

GEORGE A. SEIB.
